UNITED STATES PATENT OFFICE.

JOHN HOWARD MASTERS, OF DAYTON, OHIO, ASSIGNOR TO THE VALLE-KIMES COMPANY, OF DAYTON, OHIO, A CORPORATION OF OHIO.

TANK-BASE CASTING.

1,366,538.

Specification of Letters Patent. Patented Jan. 25, 1921.

Application filed December 9, 1919. Serial No. 849,603.

To all whom it may concern:

Be it known that I, JOHN HOWARD MASTERS, a citizen of the United States, and residing at Dayton, in the county of Montgomery and State of Ohio, have invented a new and useful Improvement in Tank-Base Castings, of which the following specification is a full disclosure.

This invention relates to a base casting 10 adapted to have mounted upon its upper annular portion a tank or reservoir, and upon its upper rectangular portion, a pump-base casting or any similar casting, for the support of a suitable pump mechanism for operative connection with the said tank.

It has been the practice to cast these bases in a single piece and in so doing a large amount of time has been consumed and material wasted. An advantage in casting the 20 parts of this base separately and providing means for locking the said parts together to form a complete base is to very materially reduce the cost of the manufacture. Specifically, an actual reduction in foundry 25 cost is thirty-three and one-third per cent., with a fifty per cent. increase of production by the molder. An additional advantage is the application of lugs to the upper side of the annular portion of my casting for securely seating a tank.

Other advantages will appear in the specification and drawings and will be specifically referred to in the claims.

Figure 1 is a top plan view of my complete base-casting.

Fig. 2 is a reverse plan of the same.

Fig. 3 is an enlarged fragmentary reverse plan of the central locking means.

Fig. 4 is an enlarged end view of the male 40 member.

Fig. 5 is an enlarged end view of the female member.

Fig. 6 is an enlarged fragmentary reverse plan of one of the base locks.

Fig. 7 is an enlarged end view of the female member of the same.

Fig. 8 is a similar view of the male member.

The base for a combined tank and pump 50 comprises three castings respectively interlocked together, there being a rectangular casting 1, having the rim flange 2, on its under side, portions of the rim on one of the sides being cut out to form the locking recesses 3, 3', for the segments of the annular

casting. This annular casting for supporting the tank is made in two separate segments 4, 5, respectively, counterparts of one another. The ends of these segments adjacent the casting 1 are formed with the 60 lock lugs 6, 7, adapted to interlock into the recesses 3, 3', of the rim of casting 1. These segments are formed with outer and inner rims 8, 9, on the under side, and with the bracing cross ribs 10, 11, 12. The interlock 65 for the abutting ends of these segments 4, 5, consists of a lock lug 13 cast on the under side of the member 5 between the rims and having a latch projection 14, fitting into the recess 15 of the inner rim of the abutting segment 4, the major portion of this block projecting endwise beyond the end of member 5 and into the space between the rims of the abutting member 4. On the upper face of these segments are cast three 70 lugs 16 for securely seating the tank on the annulus formed by the interlocked segments. These segments are securely interlocked in relation to one another and to the member 1, forming a strong, unitary base for a combined tank and pump.

Having described my invention, I claim:

1. A base for supporting a combined pump and tank, consisting of a rectangular casting, and two segments of an annulus, all 85 of said castings being formed with flange rims on their under sides, the abutting portions of the segments and rectangular castings being formed with interlocking lugs and recesses, and the abutting ends of the 90 two segments being formed with a lug and recess interlock, the recesses being formed in portions of the rims of the respective castings.

2. A base for supporting a combined 95 pump and tank, comprising a rectangular casting and two segments of an annulus, all formed with flange rims on their under sides, the abutting portions of the segment and rectangular castings being formed with 100 a lug and recess interlock through a rim portion, one of the abutting ends of one of the segments being formed with a lug between its flange rims projecting beyond the end of that segment and having a latch end, 105 a rim portion of the abutting end of the adjacent segment having a locking recess, said lug projecting between the rim portions of said adjacent segment.

3. A base for supporting a combined 110

pump and tank consisting of a supporting casting for the pump and two cast members together constituting a support for the tank, all of said castings being formed with 5 flange rims on their under sides, the abutting portions of said two cast members for the tank and the casting for the pump being formed with interlocking lugs and recesses, and the abutting ends of the said two 10 cast members being formed with an interlocking lug and recess.

4. A base for supporting a combined pump and tank consisting of a supporting casting for the pump and two cast members

of a tank supporting part, the abutting portions of the said two cast members and the tank supporting casting being formed with 15 interlocking lugs and recesses, and the abutting ends of the said two cast members being formed with an interlocking lug and 20 recess.

In witness whereof, I hereunto subscribe my name, as attested by the two subscribing witnesses.

JOHN HOWARD MASTERS.
